UNITED STATES PATENT OFFICE.

GUSTAV KAUFMANN, OF ST. JOHANN-ON-THE-SAAR, GERMANY.

ILLUSTRATED GUIDE.

No. 853,089.

Specification of Letters Patent.

Patented May 7, 1907.

Application filed August 31, 1905. Serial No. 276,549.

To all whom it may concern:

Be it known that I, GUSTAV KAUFMANN, a subject of the German Emperor, residing at 19 Reichstrasse, St. Johann-on-the-Saar, in the Empire of Germany, have invented a certain new and useful Illustrated Guide, of which the following is a specification.

The object of this invention is an illustrated guide in the form of a case whose outer faces are used for picture post cards, while in the interior a small booklet which can be drawn out is contained, which booklet contains a guide for the district which is illustrated in the pictures of the post cards, so that thus a practical, useful guide for excursions is provided in a very handy form as well as a souvenir which has its interest and worth increased by the description given with the pictures.

The accompanying drawing illustrates the invention, Figure 1 being a perspective front

view, Fig. 2 a section, and Fig. 3 a perspective front view in which the guide is drawn out.

In the drawing, 1 is the front side of the post card case, 2 is the booklet or guide, and 3 is a sheet fixing the latter in the case.

What I claim as my invention and desire to secure by Letters Patent is:—

An illustrated guide comprising in combination a booklet, a case within which said booklet is contained and a folded sheet attached to the inside of said case and to said booklet for securing said booklet within said case.

In testimony whereof I have hereunto signed my name to this specification in the presence of two subscribing witnesses.

GUSTAV KAUFMANN.
